[57] CLAIM

The ornamental design for the fence, as shown and described.

DESCRIPTION

FIG. 1 is a front elevational of a fence showing a preferred embodiment of my design, the rear view being substantially the same;

FIG. 2 is an end view of the fence of FIG. 1, the opposite end view being substantially the same;

FIG. 3 is a partial top view of the fence of FIG. 1;

FIG. 4 is a partial bottom view of the fence of FIG. 1;

FIG. 5 is a rear elevational view of a second embodiment of a fence showing my design, the front is substantially the same as the front of the fence in FIG. 1;

FIG. 6 is an end view of the fence of FIG. 5, the opposite end view being substantially the same;

FIG. 7 is a partial top view of the fence of FIG. 5; and,

FIG. 8 is a partial bottom view of the fence of FIG. 5.
